UNITED STATES PATENT OFFICE

WALTER H. GREEN, OF CHICAGO, ILLINOIS, ASSIGNOR TO GENERAL ZEOLITE COMPANY,
OF CHICAGO, ILLINOIS, A CORPORATION OF ILLINOIS

BOILER CONTROL APPARATUS

Application filed February 1, 1929, Serial No. 336,863. Renewed December 9, 1931.

This invention relates to apparatus and methods of removing liquid from one or more places of high pressure to places of lower pressure. It more particularly relates to steam purifiers and to methods and means of removing the collected water and impurities therefrom, especially those systems in which a boiler blow-down and steam purifier discharge are simultaneously actuated.

In the copending application of Walter H. Green and others, Serial Number 188,104, filed May 2nd, 1927, there is disclosed a steam purifier adapted to be placed within the steam space of a boiler and in which any moisture in the steam passing out of the boiler, is removed by a series of deflecting vanes, such moisture being collected in a chamber in the lower part of such purifier.

It is desirable to remove the water and impurities, so collected from the steam, to the outside of the boiler. The water carried by the steam generated in an ordinary boiler, and removed from such steam by a purifier, contains substantially the same impurities as the water in the boiler and in about the same proportions. The more impure the water in the boiler, the more impure the steam will be due to increased turbulence, foaming or priming, accompanying the release of the steam at the water surface. Also the greater the steaming rate the greater the amount of moisture and impurities that will be entrained, so that as a general rule in order to maintain the steam of substantially constant quality it is desirable to have a lower boiler concentration at higher steaming rates than at lower steaming rates.

Since the amount of water collected by the purifier from the steam corresponds to the quantity and quality of the steam generated and since the quality decreases with higher solid concentration and higher steaming rates, the water removed from the steam by the purifier is in reality a partial blow-down of the boiler and will increase with an increase in the solid concentration and with an increase in the rate of steaming. Frequently, however, this partial blowdown is not sufficient to regulate the boiler water solid concentration in a satisfactory manner,

and it is necessary to supplement such purifier discharge by an additional boiler blowdown. This additional blowdown should also be proportional to the amount of evaporation, or more preferably proportional to both the amount of evaporation and the rate of evaporation. Since the purifier discharge is proportional to the amount of evaporation and also under certain conditions proportional to both the amount and rate of evaporation, it would be desirable to control the proportion of and/or actuate this additional blowdown by the purifier discharge.

An object of this invention is to provide a means by which the water from the collecting chamber of the steam purifier and a boiler blowdown system will be discharged simultaneously.

Another object of this invention is to provide an improved apparatus by means of which a boiler may be blown down in proportion to the quantity and quality of the steam produced and in proportion to the steaming rate.

A further object of this invention is to provide an improved apparatus for discharging one or more liquid containing chambers, which are under pressure, simultaneously to the atmosphere or to other place of lower pressure.

An especial object of this invention is to provide a combined purifier discharge and boiler blowdown system which may be actuated by means of one blow-off valve.

Other objects will appear during the course of the following description.

In the preferred form of the present invention the moisture and impurities collected from the steam purifier are conducted to one or more collecting and/or float chambers adjacent to, or removed from, the purifier. If the collecting or float chamber is positioned within the boiler drum, it may be placed either directly under the purifier or near one end of the drum. The collecting and/or float chambers or additional chambers may also be positioned outside of the boiler drum. In one embodiment of the invention one of the collecting chambers is provided with a float and cooperating latch and trip-weight.

mechanism, which are adapted to open the purifier discharge and blowdown lines simultaneously when a predetermined amount of liquid has collected therein. This float chamber 5 may be adapted to collect all the impurities and moisture separated by the steam purifier or only a portion thereof, and it may be placed within or without the boiler.

In the drawings, which show several embodiments of the invention:

Figures 1 and 2 represent a side sectional view of a boiler shell, showing the steam purifiers in position and an external float chamber;

Figures 3 and 4 are detail views illustrating the discharge and check valve arrangements and the float and trip mechanism;

Figure 5 illustrates a modification in which the float chamber is positioned within the boiler drum; and

Figures 6 and 7 illustrate details of the float mechanism and of the discharge valve.

In Figures 1 and 2 the boiler shell 11 is provided with the steam space 12 and contains a body of water 13. It is provided with a main steam outlet 14, which steam outlet communicates with the steam purifiers 15. These steam purifiers are provided with steam inlets 16 from the steam space of the boiler 12, with the purifying elements 17, and with the steam outlet connection 18 which communicates with the main steam outlet 14 of the boiler. Below the purifying elements 17 is, or are, normally positioned a chamber or chambers 19 for collecting the moisture and impurities removed from the steam in its passage through the purifier.

In the embodiment of the invention shown in Figure 1, the collecting chambers 19 are caused to drain into an enlarged collecting chamber 20 by means of the pipe 21. The enlarged collecting chamber 20 is provided with a vent 22. In the embodiment shown in Figure 2, one of the purifying elements 45 is provided with an enlarged chamber 40, which is adapted to collect separated moisture and impurities from the other smaller collecting chambers 19, as well as from its own purifying elements. The smaller collecting chambers 19 drain into the large collecting chamber 40 by means of the conduits 41. The enlarged collecting or drain chambers 20 and 40 are emptied by means of a conduit 57 which leads to the exterior of the boiler.

On the exterior of the boiler is positioned a small float chamber 50 which is placed at substantially the same level as the chamber 19, 20 and 40 within the boiler drum. This float chamber 50 (see Figure 4) is provided with a steam space 51 which communicates with the steam space 12 of the boiler by means of the pipes 53 and 55, and with a water space 52 which communicates with an internal drain or collecting chamber by means of the

conduits 56 and 57. Within the float chamber 50 (see Figure 4) is positioned a spherical float 60. This float is provided with a latch and trip weight mechanism which is adapted to cause elevation of the weight 61 during its upward motion and to release the weight when it has reached its maximum predetermined height, which will occur when the collecting chambers have all been filled with liquid to a definite level. At such time the weight will drop opening the line 62 to the atmosphere.

This will result in opening the valve 70 permitting a discharge of the collected impurities and moisture in the purifier collecting chambers and also causing a proportionate boiler blowdown. The line 62 remains open until a desired amount of discharge takes place, whereupon the float will reach a predetermined low level at which the latch and trip weight mechanism will be actuated so as to cut off the line 62 from the atmosphere and connect it to the steam space of the boiler 11. This will cause closure of the valve 70 and stop further discharge. The valve 70 will remain closed during the upward movement of the float 60.

The construction and operation of the float, trip weight and latch mechanism is more fully shown and described in a copending application Serial Number 336,691 filed February 1, 1929.

The discharge valve and its connecting conduits are shown in detail upon Figure 3. The discharge is carried through the valve 70 by means of the passages 71, 72 and 73. At the entrance of the passage 72 is the throttle valve 74 which may be adjusted so as to control the rate of discharge. The exit of the passage 72 is adapted to be closed by means of the valve 75 which is actuated by the piston 76. Steam under boiler pressure is supplied to the piston 76 by means of the conduit 62 in the periods between discharges. The main discharge passage 80 leads to passage 71. This passage receives the combined purifier and boiler discharge. The purifier discharge line 57 and the boiler blowdown line 81 are connected to the passage 80 at the fitting 82.

In both the purifier discharge and the boiler blowdown lines before the fitting 82 may be positioned the proportioning valves 83 and 84, for fixing the ratio of the purifier discharge to the boiler blowdown, and the check valves 85 and 86 for preventing a reverse flow through conduits 57 and 81. The reasons for this are readily apparent. Taking Figure 1 for purposes of exemplification, when the chamber 20 is filled to a point near its maximum level, the level therein is higher than the boiler water level and there would be a tendency for the collected moisture therein to flow into the boiler through the line 57, the fitting 82 and the line 81. When, however,

the chamber 20 has been discharged, the level of liquid therein would be lower than boiler level and there will be a tendency for the boiler water to flow into this chamber through line 81, fitting 82 and line 57. The check valves 85 and 86 will prevent such a reverse flow in either direction, permitting discharge therethrough only. In Figure 2 the check valve on the steam purifier discharge line has been eliminated since there is no possibility of the boiler water flowing into the chambers 40 and 50, said chambers being at a higher level than the boiler water line.

Figure 5 shows an arrangement in which the float chamber and the collecting chambers are positioned inside the boiler drum. The float 100 actuates a trip weight-latch-pilot valve mechanism. Figures 6 and 7 are detailed views of the float and discharge valve mechanism used in this embodiment of the invention. When the ball float 100 is in its lowermost position, as shown upon Figures 5 and 6, the valve 101 will be closed, cutting off any discharge through the purifier discharge line 102 and the boiler blowdown line 103. When the boiler is in operation, the moisture separated from the steam in the purifier sections 17 will gradually collect in the enlarged float and collecting chamber 99 until a predetermined level has been reached. At this point the ball float will release a weight or trip, which in turn will open a valve admitting boiler pressure into the line 104. This boiler pressure will be exerted against the piston 105 of the valve 101 lifting the valve member 106 from its seat. As a result discharge will commence through the purifier discharge line 102 and a boiler blow-down line 103. This discharge will continue until the ball float 100 has reached the lowest position. Thereupon line 104 will be cut off from the steam space of the boiler, piston 105 will be moved to the left, and valve member 106 will be seated closing the boiler blowdown line 103 and the purifier discharge passages. It will be noted that the boiler blowdown line is provided with a check valve 107 and that both lines are provided with proportioning valves 109 and 110 before they are combined by the fitting 111.

By regulating valves 83 and 84 (see Figure 3) or the valves 109 and 110 (see Figure 5), it is possible to secure the proper proportionment between the steam purifier discharge and the boiler discharge. Since the purifier discharge is proportional to the quality and quantity of the steam and also to the steaming rate, it is evident that the boiler blowdown will also be proportional to these factors. In the preferred arrangement of the present invention the discharge of the main body of liquid and impurities from the collecting or drain chamber of the steam purifier inside the boiler is by boiler pressure. The discharge of the liquid and impurities is

quickly accomplished in an entirely positive manner when the discharge valve is open. It is preferable to position all moving parts of the discharge mechanism outside of the boiler shell, where they may be easily cleaned, repaired and replaced as shown upon Figures 1 and 2.

If desired, the steam purifier could also be placed without the boiler shell, for example in the steam line 14. Also the collecting chamber and float chambers could be placed outside the boiler and all the separated moisture and impurities could be caused to drain by gravity thereto.

It will be noted that the present invention describes an apparatus broadly adapted to enable discharge of one or more liquid containing chambers which are under pressures higher than atmospheric, but which are at different pressures as amongst themselves. This discharge will be simultaneous and the amount of discharge from the various chambers may be regulated in the proportions desired.

What is claimed is:

1. In combination with a boiler, a steam purifier, a discharge conduit for the impurities collected by said purifier, a blow-down conduit for the boiler, a common conduit adapted to receive said purifier discharge and said blow-down and a valve upon said conduit actuated periodically by the amount of impurities collected by said purifier.

2. In combination with a boiler, a steam purifier, a chamber for receiving collected impurities, means for conducting the collected impurities from said chamber to the exterior of the boiler, means for blowing down the boiler, a conduit exterior to said boiler communicating with said impurity conducting means and said boiler blowdown means to receive said collected impurities and said blowdown, a valve upon said conduit and means actuated by the level of liquid in said chamber to control the action of said valve.

3. In combination with a boiler, a steam purifier, means for discharging said steam purifier, means for discharging the boiler, and means actuated by the amount of water discharged from said purifier for removing suitable quantities of boiler water by said boiler discharging means, the last mentioned means comprising a common conduit adapted to receive the combined steam purifier and boiler discharge, a valve upon said conduit, a chamber for receiving steam purifier discharge and means for actuating said valve which is in turn actuated when a certain amount of liquid is collected in said chamber.

4. In combination with a boiler, a means for separating the moisture in steam, a collecting chamber for said moisture, a blow-down line from said boiler, a valve upon said line means actuated by the separated mois-

ture in said collecting chamber to control said valve, a conduit for discharging the collecting chamber into said blow-down line before said valve and means for preventing reverse flow in said conduit.

5. In combination with a boiler, a steam purifier, means for admitting steam to said purifier, a conduit for removing purified steam from said purifier and conveying it to 10 the steam outlet of the boiler, a conduit for draining the impurities to without the boiler shell, a boiler blow-down line leading into said drainage conduit, a valve upon said drainage conduit positioned after the place 13 of joinder of the blow-down line and the drainage conduit and means for controlling said valve governed by the amount of drainage.

6. In combination with a boiler, a valved 20 blow-down line, means for removing the moisture from the steam, a collecting chamber for moisture so removed, a line for discharging said collecting chamber, said last mentioned line joining with said first mentioned line before the valve, means for preventing reverse flow in either of said lines before the place of jointure, a float in said chamber and means actuated by said float to control the valve on the blow-down line.

30 7. In combination with a boiler, a blow-down line, a piston operated valve upon said blow-down line, a steam purifier in the steam space of said boiler shell, a collecting chamber for receiving the impurities removed 35 from the steam, a discharge line for said collecting chamber joining with said blow-down line before the valve, means for preventing reverse flow in either of said lines before their point of jointure, a float chamber, a pressure fluid line to said above mentioned piston operated valve, and a valve upon said fluid pressure line controlled by the movement of the float in said float chamber.

45 8. In combination with a boiler control, a blow-down line, a piston operated valve upon said blow-down line, a steam purifier, a float chamber, a liquid line from said purifier to said float chamber, a discharge line from said float chamber leading to the valve chamber 50 of above mentioned piston operated valve, means for preventing reverse flow in said blow-down line or said discharge line, a pressure fluid line leading to the piston cylinder of said above mentioned piston operated 55 valve, and a valve upon said fluid pressure line governed by the movement of the float in said float chamber.

9. In combination with a boiler, a steam 60 purifier, a collecting chamber below said purifier, discharge lines from said collecting chamber and from the water space of the boiler, said lines uniting in a common discharge line, a piston-operated valve on said common discharge line outside of the boiler, 65 means for admitting fluid pressure to and for

cutting off fluid pressure from the piston of said piston-operated valve, and means for preventing flow from said water space to said collecting chamber or from said collecting chamber to said water space.

70 10. In combination with a boiler, a steam purifier, a collecting chamber below said purifier, a discharge line from said collecting chamber extending outside of the boiler, a blow-down line, a combined line connecting with said discharge and blow-down lines, a valve on said combined line outside of the boiler, means for preventing reverse flow in either the blow-down line or the discharge line, and means for governing said valve 80 controlled by the liquid level in the collecting chamber.

11. In an apparatus for simultaneously discharging liquid containing chambers which are under a higher pressure than atmospheric to the atmosphere, a piston operated valve one side of which is connected to a point of atmospheric discharge, a series of discharge lines leading to said piston operated valve, a fluid pressure line leading to 85 said piston and having means to admit or cut off fluid from the piston of said valve, a float in one of said chambers, a trip mechanism actuated by said float, a valve actuated by said trip mechanism 90 adapted to open or close said fluid pressure line, check valves in each of said discharge lines adapted to prevent reverse flow therein and proportioning valves in each of said lines adapted to proportion the flows in the various lines.

95 12. In combination with a boiler, a steam purifier, a collecting chamber for said purifier, a float responsive to the level in said collecting chamber, a discharge conduit from said chamber, a blowdown conduit from the boiler, a common discharge valve for said discharge conduit and said blowdown conduit, a pilot valve actuated by said float, and means in association with said pilot valve for 100 controlling said discharge valve.

110 In testimony whereof I have hereunto subscribed my name.

WALTER H. GREEN.
